UNITED STATES PATENT OFFICE.

WILLIAM D. FORSYTH, OF YOUNGSTOWN, OHIO, ASSIGNOR OF ONE-HALF TO
ALEXANDER M. NEEPER, OF PITTSBURGH, PENNSYLVANIA.

EXPANDED METAL.

1,019,034.

Specification of Letters Patent.

Patented Mar. 5, 1912.

Application filed January 30, 1911. Serial No. 605,624.

To all whom it may concern:

Be it known that I, WILLIAM D. FORSYTH, a citizen of the United States, residing at Youngstown, in the county of Mahoning, in the State of Ohio, have invented new and useful Improvements in Expanded Metal, of which the following is a specification.

My invention relates to new and useful improvements in expanded metal adapted to be used in the construction of buildings, the roofs, walls and partitions thereof, and for reinforced concrete construction.

My invention consists of a novel expanded metal having longitudinal members transversely connected by independent disconnected corrugated meshed members which together with said longitudinal members are formed from the same sheet of metal.

My improved sheet metal is shown in the accompanying drawings which form part of this specification.

Figure 1 represents a sheet of metal with series of longitudinal and transverse slits made therein preparatory to forming the longitudinal and meshed members of my improved expanded metal. Fig. 2 shows the slitted sheet corrugated so that the one series of longitudinal slits will coincide with the bases of the corrugations and the other longitudinal series of slits with the apexes of said corrugations. Fig. 3 shows the end view of my improved expanded metal with the longitudinal members ribbed and the meshed members corrugated. Fig. 4 is a plan view of sheet X of Fig. 1 when stretched laterally. Fig. 5 shows sheet X in plan showing the transverse slits distributed differently from the transverse slits of sheet X in Fig. 1. Fig. 6 is a plan view of sheet X', Fig. 5, stretched laterally.

Similar figures and letters of reference refer to like parts throughout the several figures.

In Fig. 1, X is a sheet of metal in which a, b and c represent the longitudinal members of my improved expanded metal. 1, 1', 1'', 1''', 1'''', t and 2, 2', 2'', 2''', represent slits made in said sheet in two parallel series, S, S'. The slits 1, 1', 1'', 1''', 1'''' and 50 t, when the sheet of metal X is stretched laterally, form the outside edges of the meshed members of my improved expanded metal. The slits 2, 2', 2'', 2''', form the apertures in the meshes of my expanded metal, the slits 1, 1', 1'', 1''', 1'''' coinciding

with the bases of the corrugations thereof, and the slits 2, 2', 2'', 2''' coinciding with the apexes of the corrugations thereof. The relations of the longitudinal members a, b and c and the corrugated meshed members 60 of my expanded metal when the sheets are stretched, are shown in Fig. 2.

The series of slits S, S', may be formed by rolls having proper cutters arranged to perforate the sheet to be expanded, with slits 65 in the positions shown in Fig. 1 of the drawing, said slits being longitudinal at 1, 1', 1'', 1''', 1'''' and at 2, 2', 2'', 2''', and transverse at t. After said slits have been passed through suitable rolls to perforate the metal 70 the sheet is again passed through another pair of rolls to form the corrugations therein so that the perforations represented by slits 1, 1', 1'', 1''', 1'''' shall be at the bases of the corrugations and the perforations represented by slits 2, 2', 2'', 2''' shall be at the apexes of said corrugations. The sheet 75 may then be passed through another pair of rolls, one of which is provided with a tongue and the other with a proper groove so as to form the longitudinal members a, b and c into ribs as shown in Fig. 3 at a', b' and c'. After these operations, the slitted and ribbed sheet is stretched laterally with the result that my improved expanded metal is formed 80 having longitudinal members and corrugated meshed members, said meshed members separating at their ends at the slit t and drawing away from one another at their extremities so that the longitudinal 85 members of the sheet being operated upon are not materially distorted or shortened, the shortening of the sheets treated when expanded being taken up in the movements of the meshed members within themselves, 90 95 the ends of said meshed members approaching one another as the stretching takes place and separating from the ends of adjacent meshed members.

In Fig. 5, sheet X' is slitted with two 100 series of longitudinal slits, 3, 3, 3, 3, 3, 3, and 4, 4, 4, 4, 4. The transverse, 5, 6, 7, slits are made the same as transverse slits t on sheet X in Fig. 1. The transverse slits, 5, 6, 7, on sheet X' extend from the parallel 105 slit 3 coincident with the edge of the longitudinal member a across all of the longitudinal slits, 3, 3, 3, 3, 3, to longitudinal slit 3 which is coincident with the edge of longitudinal member b. Longitudinal slits 110

4', f', on sheet X', Fig. 5, extend respectively from the second longitudinal slit to the third longitudinal slit and from the fourth longitudinal slit to the fifth longitudinal slit of the series of longitudinal slits, 3, 3, 3, 3, 3, 3. It will be noted that these transverse slits 4', 4', do not extend from the edges of the longitudinal members. Transverse slits 4'', 4'', 4'' extend from the 10 first to the second, from the third to the fourth and from the fifth to the sixth longitudinal slits of the series 3, 3, 3, 3, 3, 3, the transverse slits, 4'', 4'', adjacent to the longitudinal members a and b of sheet X' extending to the first and last longitudinal slits of the series 3, 3, 3, 3, 3, 3.

It will be noted that the distribution of the transverse slits upon sheet X' is different from the distribution of the transverse slits 20 on sheet X in Fig. 1. The transverse slits t on sheet X in Fig. 1 occurring at each series of five longitudinal slits, so that the meshed members connecting the longitudinal members of sheet X when stretched laterally form meshed members having a single line of meshes, each with a single aperture connecting at the ends with the longitudinal members and with each other between the end meshes forming the connecting meshed member.

Between the transverse slits 5 and 6 on sheet X' occur the transverse slits 4', 4', and two groups of longitudinal slits 4, 4, 4, 4, 4, and one group of longitudinal slits, 3, 3, 3, 35 3, 3, 3, four of the last mentioned longitudinal slits being connected by transverse slits 4', 4'. When the sheet X' is stretched laterally the meshed member formed by the slitted portion of it between transverse slits 40 5 and 6, Fig. 5, is included between the openings a', a' on Fig. 6. The meshed member thus constructed has an opening a' at each of its ends and has three parallel series of apertures in its meshes, extending across the 45 sheet and also within the meshed member itself. The terminals b', b' occur because of the presence of the longitudinal slits 4', 4' in the sheet X' and the stretching of said sheet X' on like principle makes the meshed 50 member at the top of sheet X' as shown in plan in Fig. 6. The only difference between the meshed member between a', a' and the one at the top of the sheet being the difference in the distribution of the transverse 55 slits 4', 4' from the distribution of the transverse slits 4'', 4'', 4'' in the next higher member.

The different members of the sheet from which my improved expanded metal is to 60 be made have hereinbefore been designated as "longitudinal members" and "meshed members." The longitudinal member thus designated consists of the entire metal section left in the sheet after the slits have been 65 made therein for the production of the

meshed or reticulated portion thereof and where the longitudinal members are referred to by such terms as "longitudinal members," such terms may be read as synonymous with the term "entire metal section" for the purposes of this specification and the claims thereof. The meshed member consists of that portion of the sheet which has been slitted twice longitudinally and once transversely, stretched laterally. These meshed members when so treated form the reticulated metal sections which connect the entire metal sections of my improved expanded metal at intervals within the confines of the sheet from which it is made and the terms 70 "meshed member," "reticulated metal section" and "reticulated section" are synonymous when used in this specification and the claims thereof.

On January 30, 1911, I filed another application for improvements in expanded metal which bears the Serial No. 605,625. The expanded metal therein described is the product derived from the exercise of the process described in my application filed December 12, 1910, for process of making expanded metal, which bears Serial No. 596,761. A reference to the last named application will disclose that the product of the process therein described is made by the 85 exercise of said process, consisting of four operations, to-wit: the first and second slitting the sheet longitudinally; the third, slitting said sheet at its slitted portion transversely; the fourth, stretching the sheet so 90 slitted in two directions laterally. The stretching of the sheet results in reticulated sections wherein the strands of metal surrounding the meshes in the reticulated section fall into that position which is normally assumed by the meshes of any expanded metal slitted and stretched for the production of diamond meshed expanded metal without distortion or stretching the metal.

The expanded metal described and claimed in this application is the product of the process described and claimed in my application No. 596,763, filed December 12, 1910. A reference to the last mentioned application will disclose the fact that the expanded metal described and claimed in this application is the result of the process described in said application and the result of the five operations of said process 100 upon a sheet of metal, to-wit: the first, second and third, the same as in the process described and claimed in application No. 596,761; the fourth operation is the corrugating of the slitted portion of the sheet so 105 that the bases of the corrugations will coincide with the points of connection of the reticulated sections with the entire metal sections and the points of connection between the meshes themselves of the reticulated sec- 110 115 120 125 130

tions and so that the medial lines of the meshes of said reticulated sections will substantially coincide with the apexes of said corrugations. The fifth operation is the 5 stretching of the sheet laterally when slit thus in two directions and the sheet corrugated at its slit portions.

In the expanded metal described in the application No. 606,625, the strands of the 10 meshes of the reticulated sections are in the position normally assumed by the strands of the meshes of metal when expanded to make diamond expanded metal.

In the expanded metal described and 15 claimed in this application, the strands of the meshes are in that position into which they are forced by the corrugation of the slit portion of the sheet before the sheet from which said expanded metal is made, is 20 stretched laterally.

The longitudinal members are shown in the drawing to be different in number; they may be any number desired within the limits in size of the sheet and the lines of meshed 25 members to be formed, and while the meshed members are shown of a given number in the drawing, that number may be changed, being made greater or less as may be desired for any particular use. All of these variations in form may be made without departure from the spirit of my invention. 30

What I claim as my invention is—

1. An expanded metal made from a single sheet having substantially parallel sections 35 of entire metal connected at intervals by reticulated metal sections which are disconnected from each other between the entire metal sections, and which are corrugated so that the apexes of the corrugations thereof 40 coincide substantially with the medial lines of the openings of the meshes thereof, and the bases of said corrugations coincide substantially with the points of connection of said meshes with each other and with the 45 entire metal sections.

2. An expanded metal made from a single sheet having substantially parallel sections of entire metal connected at intervals by reticulated metal sections which are disconnected from each other between the entire 50 metal sections, and which are corrugated so that the apexes of the corrugations thereof

coincide substantially with the medial lines of the openings of the meshes thereof and the bases of the said corrugations coincide 55 substantially with the points of connection of said meshes with each other and with the entire metal sections, said entire metal sections being corrugated longitudinally.

3. An expanded metal made from a single sheet having substantially parallel sections of entire metal connected at intervals by reticulated metal sections which are disconnected from each other between the entire metal sections, and which are corrugated so 60 that the apexes of the corrugations thereof coincide substantially with the medial lines of the openings of the meshes thereof and the bases of said corrugations coincide substantially with the points of connection of 65 said meshes with each other and with the entire metal sections, said reticulated metal consisting of meshes, the individual meshes being joined together in direction of expansion of said metal and disconnected in direction 70 at right angles to the expansion of said metal.

4. An expanded metal made from a single sheet having substantially parallel sections of entire metal connected at intervals by reticulated metal sections which are disconnected from each other between the entire metal sections, and which are corrugated so 75 that the apexes of the corrugations thereof coincide substantially with the medial lines of the openings of the meshes thereof and the bases of said corrugations coincide substantially with the points of connection of said meshes with each other and with the entire metal sections, said reticulated metal 80 consisting of meshes, the individual meshes being joined together in direction of expansion of said metal and disconnected in direction 85 at right angles to the expansion of said metal, said entire metal sections being corrugated longitudinally.

In testimony whereof I have signed this specification in the presence of two subscribing witnesses.

WILLIAM D. FORSYTH.
